ELECTRON DISCHARGE DEVICE

Leon S. Nergaard, Verona, N. J., assignor to Radio Corporation of America, a corporation of Delaware

Application October 30, 1941, Serial No. 417,122

18 Claims.

(Cl. 250—27.5)

My invention relates to electron discharge devices, more particularly to such devices useful at ultra high frequencies.

It is desirable to have an output system having low impedance suitable for operation with broad band circuits in the ultra high frequency field and to have an electron discharge device which may be incorporated in such a system. It is further desirable to eliminate high frequency losses normally encountered in bringing high frequency leads through the envelope of the electron discharge device. Another desirable feature is to be able to separate electrically and physically the output electrodes from the current collector so that the power dissipating ability of the output electrodes imposes no limitation on the power output.

It is, therefore, an object of my invention to provide an electron discharge device suitable for use at high frequencies and capable of use with output systems having a low output impedance and suitable for operation with broad band circuits.

It is another object of my invention to provide an electron discharge device suitable for use at high frequencies and which avoids the use of high frequency leads extending through the tube envelope, thus reducing high frequency losses.

Another object of my invention is to separate the current collector and output electrodes so that the power dissipating ability of the electrodes imposes no limitation on the power output. These and other objects will appear hereinafter.

Recently there has been developed what has been termed velocity modulation for use at ultra high frequencies. In the arrangements proposed the electrons of an electron beam or stream are given varying velocities, the variation in velocity being applied cyclically so that the beam comprises slow and fast electrons. As a result at predetermined points the fast electrons overtake the slow electrons, producing groups or bunching. When groups have been bunched it is possible to extract energy from the beam by proper electrode arrangements either inductively or by absorption by absorption electrodes. This method of producing slow and fast electrons in a beam has proved particularly useful at ultra high frequencies.

It is, therefore, another object of my invention to provide an improved electron discharge device utilizing velocity modulation and particularly such a device utilizing the desirable characteristics of a magnetron.

A still further object of my invention is to provide an electron discharge device suitable for use at high frequencies, particularly such a device capable of use as a mixer in superheterodyne reception at high frequencies.

The novel features which I believe to be char-

acteristic of my invention are set forth with particularity in the appended claims, but the invention itself will best be understood by reference to the following description taken in connection with the accompanying drawings in which Figure 1 is a schematic longitudinal section of an electron discharge device and associated circuit made according to my invention, Figure 2 is a transverse section taken along line 2—2 of Figure 1, and Figure 3 is a longitudinal schematic showing of a modification of the device shown in Figure 1.

As shown in the drawings in Figures 1 and 2, an elongated envelope 10 has positioned at one end an indirectly heated cathode 11 provided with a heater 11'. A grid 9 may be provided adjacent the cathode either for modulation purposes or as a space charge grid. This grid is provided with an extended collar 9' closely adjacent the tube wall for purposes to be described. Mounted at the other end of the envelope is a collector 12 for collecting electrons in the beam supplied by the cathode 11. Positioned along the envelope are a pair of accelerating and screen electrodes 13 and 14 having applied thereto proper voltages for maintaining the neighboring space at a potential high enough to prevent reflection of electrons and to accelerate the electrons down along the length of the tube. A suppressor and screen 15 is positioned adjacent the collector 12. A tank circuit is provided by surrounding the envelope with a resonant cavity tank circuit 16 provided with a slot or gap 17 surrounding the discharge path between the accelerating electrodes 13 and 14. The edges of the cavity include a pair of electrodes merged into the cavity. The R.-F. field generated across the gap during operation of the device results in velocity modulation of the electron beam. This tank circuit may be used as an input circuit under certain conditions or as a local oscillator circuit under other conditions, as will be described.

The output electrodes comprise a pair of anode segments 19—20 surrounding the outside of the tube envelope and connected to the conductors 21 forming part of a transmission line tank circuit. A rod 22 maintained during operation at substantially cathode potential serves to provide an outwardly directed radial electrostatic field. This field in combination with a longitudinal magnetic field causes the electrons to pass close to the tube envelope wall when the apparatus is in operation, the electrode 15 acting as a suppressor and screen. The rod 22 also serves to reduce the axial longitudinal velocity of the electron stream as a whole. The output circuit is completed by means of a shorting bar or disc 21' slidably on the conductors 21 and contacting the shielding compartment 23 on the interior to completely shield the output electrodes

and output circuit to prevent undesired radiation. The output is obtained by means of a coupling loop 24. The magnetic field for maintaining the beam focused and for causing electrons when passing through the output system to follow spiral orbital paths is provided by means of electromagnets 25 and 26. Heating current is supplied from source 27 and voltages for the output circuit and other electrodes are furnished by means of voltage source 28. The voltage source 27' provides the proper bias for the grid 9.

The electron discharge device just described is also particularly suitable for use as a mixer when superheterodyne reception is employed. When so used, a Lecher wire system comprising the conductors 33 and shorting bar 34 are connected between the cathode 11 and grid 9, the input signal being coupled to the Lecher wire system by means of the loop 32. The cathode is coupled to one of the Lecher wire conductors by means of the capacity 34. Thus it is possible to introduce the input signal by means of the Lecher wire system and the local oscillator voltage by means of the coupling loop 16' and tank 16, the intermediate frequency being extracted by the output circuit comprising conductors 21 and shorting disc 21' coupled to the loop 24. When it is not desired to introduce a signal on the grid and to use the grid merely as a focusing grid, the shorting bar may be removed or moved close to the tube envelope.

When operated with no R.-F. signal on the grid the electron stream is focused by the grid 9 and accelerated by electrode 13, these two electrodes being maintained at the same R.-F. potential by the by-passing action of collar 9' coupled to the inner conductor of tank circuit 16 to which electrode 13 is connected. In passing across gap 17 of tank 16, the stream of electrons is velocity modulated, after which the electrons enter the output space through accelerating electrode 14, which serves to maintain the neighboring space at a potential high enough to prevent reflection of electrons. The number of spirals which the electrons perform in moving axially through the output electrodes depends on the axial velocity. The output varies with the velocity modulation impressed on the beam by the applied signal. In the space between the anode segments 19 and 20, the electrons perform spiral orbits, as in magnetrons, and give up a fraction of their energy to the output electrode segments 19 and 20 each time they cross the slot field of the output electrodes. The fast moving electrons take orbits having larger radii than the slow moving electrons which follow by approximately 180° in phase. The fast electrons hence come closer to the gap field giving up more energy than the slower electrons may absorb. The time of one orbit may be matched to a period of the input frequency to provide proper phase relationship between input and output. The effective current from which the output electrodes obtain power is thus the product of beam current and the number of spirals. Since this effective current is large, the tube is capable of driving a low impedance load, such as encountered in wide-band transmission. After giving up their energy, the electrons are collected by a collector electrode 12.

The input voltage to drive the input tank circuit 16 is fed to the tank circuit by means of the coupling loop 16', and the output voltage is

taken from the output circuit 21 through the loop 24, the output circuit being tunable by means of shorting disc 21' sliding between the shielding compartment 23 having extension 23' longitudinally of the envelope and shielding the suppressor 15 and collector 12.

When used for superheterodyne reception an input signal is applied to the Lecher wire system 33 and thus the electrons are modulated by grid 9, the modulated stream being accelerated by electrode 13 and velocity modulated with the oscillator voltage at gap 17. The intermediate frequency voltage is extracted by means of the electrodes 19 and 20 and the intermediate frequency taken from the circuit 21 and 21' by means of the loop 24.

In Figure 3 the same numerals indicate the same elements as in Figures 1 and 2. However, in this modification the resonant cavity tank circuit is provided with a pair of tubular electrodes 30-31 electrically connected to the tank circuit on opposite sides of the gap, the electrode 30 being provided with the rod 32. The wire electrode or rod 32, which is concentric with the electrode 31, produces a radial electric field between 31 and 32. This field varies in strength with the applied signal. Therefore, as the beam formed by the cathode and grid passes through the member 31 it receives a radial component of velocity proportional to the signals. The tubular electrodes 15, 30 and 31 are operated at sufficiently high potentials to prevent electron reflection. When the electrons pass through the output space they perform spirals whose radii depend on the magnetic field strength, the potential of the output electrodes, and the radial velocity of the electrons as they enter the space. The electrons having the greater radial velocity on entering the output space will approach the output electrodes more closely than those entering with lower radial velocity, and will, therefore, give up more energy in passing through the slot field. Hence, in this modification the output is controlled by varying the radial velocity of the beam. Again a large number of spirals is performed, hence the effective output current is large and the tube can operate with a broadband circuit.

In connection with electrodes 30-31 and rod 32, when the field across gap 17 is an accelerating field, such that electrons are accelerated across the gap, rod 32 is at a lower potential than the electrode 31 and the radial field is outward causing the fast moving electrons to move outwardly closer to the inner wall of the tube envelope. On the other hand if the electrons in passing across the gap are subjected to a retarding field, thus reducing the velocity of the electrons, the rod 28 is at a more positive potential and there is a tendency to draw the slow moving electrons in close to the axis of the tube. Thus the fast and slow electrons are not only separated axially along the tube but also radially, the faster moving electrons approaching more closely the tube wall and thus delivering greater energy to the anode segments.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without depart-

ing from the scope of my invention as set forth in the appended claims.

What I claim as new is:

1. An electron discharge device having means for supplying a beam of electrons, means for velocity modulating said beam of electrons and an electrode for receiving electrons in said beam, output electrode means positioned between said velocity modulating means and the receiving electrode and comprising a plurality of segments surrounding the path of the beam and provided with gaps between said segments, means including a rod within and coaxial with said segments and magnetic means for causing electrons of said velocity modulated beam to follow spiral orbital paths within the output electrode means a plurality of times past the gaps between the plurality of segments and then toward the receiving electrode.

2. An electron discharge device having means for supplying a beam of electrons, an electrode for receiving electrons in said beam, output electrode means including a plurality of electrode segments surrounding the path of the beam and separated by gaps extending along the axis of said beam, means positioned between the beam supplying means and the output electrode means, including electrodes surrounding the path of said beam and spaced by a gap lying in a plane transverse to the path of the beam, and means for causing electrons to follow orbital paths through said output electrode means including means for producing a magnetic field along the axis of and parallel to the axis of said electron discharge device.

3. An electron discharge device having means for supplying a beam of electrons, an electrode for receiving electrons in said beam, output electrode means including a plurality of electrode segments surrounding the path of the beam and separated by gaps extending along the axis of said beam, means positioned between the beam supplying means and the output electrode means, including electrodes surrounding said beam and spaced by a gap lying in a plane transverse to the path of the beam, means for causing electrons to follow orbital paths through said output electrode means including means for producing a magnetic field along the axis of said electron discharge device, and a rod positioned coaxially of said output electrode means and adapted to be maintained at cathode potential during operation of said electron discharge device, a conductor connected to one of said electrode segments and another conductor connected to another electrode segment, and means electrically connecting said conductors together remote from said segments to provide an output circuit.

4. An electron discharge device having means for supplying a beam of electrons, an electrode for receiving electrons in said beam, output electrode means including a plurality of electrode segments surrounding the path of the beam and separated by gaps extending along the axis of said beam, means positioned between the beam supplying means and the output electrode means, including electrodes surrounding said beam and spaced by a gap lying in a plane transverse to the path of the beam, a resonator surrounding said path, said last electrodes being electrically connected to said resonator, means for causing electrons to follow orbital paths through said output electrode means and including means for producing a magnetic field along the axis of said electron discharge device, and a rod positioned

10 coaxially of said output electrode means and adapted to be maintained at cathode potential during operation of said electron discharge device, a conductor connected to one of said electrode segments and another conductor connected to another electrode segment, and means electrically connecting said conductors together remote from said segments to provide an output circuit, and shielding means surrounding said output electrodes and said conductors.

5. An electron discharge device having an elongated envelope and containing a cathode for providing a stream of electrons, and a collector for collecting said electrons, a resonator surrounding said envelope and provided with a gap surrounding said envelope adjacent said cathode, for providing a radio frequency field for velocity modulating the electrons from said cathode, a pair of accelerating and screen electrodes within said envelope and positioned on opposite sides of said gap, an output electrode system positioned between said velocity modulating resonator and said collector, and having electrode segments surrounding said envelope, said segments being spaced by gaps extending along said envelope, and means for causing the electrons to follow orbital paths through said output electrode system and including means for producing an electromagnetic field within said output electrode system and parallel to the longitudinal axis of said envelope, and a rod electrode positioned axially within said electrode segments and adapted to be maintained at cathode potential during operation of said electron discharge device, and a conductor connected to one of said electrode segments and a second conductor connected to another electrode segment and parallel to the other conductor, and means connecting said conductors together remote from said segments for providing an output transmission line circuit and a shield surrounding said output electrode system and said conductors.

6. An electron discharge device having an elongated envelope and containing a cathode for providing a stream of electrons, and a collector for collecting said electrons, a resonator surrounding said envelope and provided with a gap surrounding said envelope adjacent said cathode for providing a radio frequency field for velocity modulating the electrons from said cathode, an output electrode system positioned between said resonator and said collector, and having electrode segments surrounding said envelope, said segments being spaced by gaps extending along said envelope, and means for causing the electrons to follow orbital paths through said output electrode system and including means for producing an electromagnetic field within said output electrode system and parallel to the longitudinal axis of said envelope.

7. An electron discharge device having an elongated envelope and containing a cathode for providing a stream of electrons, and a collector for collecting said electrons, a resonator surrounding said envelope and provided with a gap surrounding said envelope adjacent said cathode for providing a radio frequency field for velocity modulating the electrons from said cathode, a pair of accelerating and screen electrodes within said envelope and positioned on opposite sides of said gap, an output electrode system positioned between said velocity modulating resonator and said collector, and having electrode segments surrounding said envelope, said segments being spaced by gaps extending along said envelope,

- and means for causing the electrons to follow orbital paths through said output electrode system and including means for producing an electromagnetic field within said output electrode system and parallel to the longitudinal axis of said envelope.

8. An electron discharge device having an elongated envelope and containing a cathode for providing a stream of electrons, and a collector for collecting said electrons, a resonator surrounding said envelope and provided with a gap surrounding said envelope adjacent said cathode for providing a radio frequency field for velocity modulating the electrons from said cathode, a pair of accelerating and screen electrodes within said envelope and positioned on opposite sides of said gap, an output electrode system positioned between said velocity modulating resonator and said collector, and having electrode segments surrounding said envelope, said segments being spaced by gaps extending along said envelope, and means for causing the electrons to follow orbital paths through said output electrode system and including means for producing an electromagnetic field within said output electrode system and parallel to the longitudinal axis of said envelope, and a rod electrode positioned axially within said electrode segments and adapted to be maintained at cathode potential during operation of said electron discharge device.

9. An electron discharge device having an elongated envelope and containing a cathode for providing a stream of electrons, and a collector for collecting said electrons, a resonator surrounding said envelope and provided with a gap surrounding said envelope adjacent said cathode for providing a radio frequency field for velocity modulating the electrons from said cathode, a pair of accelerating and screen electrodes within said envelope and positioned on opposite sides of said gap, an output electrode system positioned between said velocity modulating resonator and said collector, and having electrode segments surrounding said envelope, said segments being spaced by gaps extending along said envelope, and means for causing the electrons to follow orbital paths through said output electrode system and including means for producing an electromagnetic field within said output electrode system and parallel to the longitudinal axis of said envelope, and a first conductor connected to one of said electrode segments and a second conductor connected to another electrode segment and parallel to the first conductor, and means connecting said conductors together remote from said segments providing an output transmission line circuit and a shield surrounding said output electrode system and said conductors.

10. An electron discharge device having an elongated envelope and containing a cathode for providing a stream of electrons, and a collector for collecting said electrons, a resonator surrounding said envelope and provided with a gap surrounding said envelope adjacent said cathode, a pair of electrodes within said envelope and connected to said resonator on opposite sides of said gap for providing a radio frequency field therebetween for velocity modulating the electrons from said cathode, and a rod-electrode extending axially of one said accelerating electrode and electrically connected to the other of said electrodes and an output electrode system positioned between said resonator and said collector, and having electrode segments surrounding said envelope, said segments being spaced by gaps extending along said envelope, and means for causing the electrons to follow orbital paths through said output electrode system and parallel to the longitudinal axis of said envelope, and a rod electrode positioned axially within said electrode segments and adapted to be maintained at cathode potential during operation of said electron discharge device.

11. An electron discharge device having an elongated envelope and containing a cathode for providing a stream of electrons, and a collector for collecting said electrons, a resonator surrounding said envelope and provided with a gap surrounding said envelope adjacent said cathode, a pair of electrodes within said envelope and connected to said resonator on opposite sides of said gap for providing a radio frequency field therebetween for velocity modulating the electrons from said cathode, and a rod-electrode extending axially of one of said electrodes and electrically connected to the other of said electrodes and an output electrode system positioned between said velocity modulating resonator and said collector, and having electrode segments surrounding said envelope, said segments being spaced by gaps extending along said envelope, and screen and accelerating electrodes positioned on opposite sides of said output electrode system, and means for causing the electrons to follow orbital paths through said output electrode system and including means for producing an electromagnetic field within said output electrode system and parallel to the longitudinal axis of said envelope, and a rod electrode positioned axially within said electrode segments and adapted to be maintained at cathode potential during operation of said electron discharge device.

12. An electron discharge device having an elongated envelope and containing a cathode for providing a stream of electrons, and a collector for collecting said electrons, a resonator surrounding said envelope and provided with a gap surrounding said envelope adjacent said cathode, a pair of electrodes within said envelope and connected to said resonator on opposite sides of said gap for providing a radio frequency field therebetween for velocity modulating the electrons from said cathode, and a rod-electrode extending axially of one of said electrodes and electrically connected to the other of said electrodes and an output electrode system positioned between said velocity modulating resonator and said collector, and having electrode segments surrounding said envelope, said segments being spaced by gaps extending along said envelope, and means for causing the electrons to follow orbital paths through said output electrode system and including means for producing an electromagnetic field within said output electrode system and parallel to the longitudinal axis of said envelope, and a conductor connected to one of said electrode segments and a second conductor connected to another electrode segment and parallel to the other conductor, and means connecting said conductors together remote from said segments providing an output transmission line circuit and a shield surrounding said output electrode system and said conductors.

13. An electron discharge device having an elongated envelope and containing a cathode for providing a stream of electrons, and a collector for collecting said electrons, a resonator surrounding said envelope and provided with a gap surrounding said envelope adjacent said cathode,

a pair of electrodes within said envelope and connected to said resonator on opposite sides of said gap for providing a radio frequency field therebetween for velocity modulating the electrons from said cathode, and a rod-electrode extending axially of one of said electrodes and electrically connected to the other of said electrodes and an output electrode system positioned between said resonator and said collector, and having electrode segments surrounding said envelope, said segments being spaced by gaps extending along said envelope, and accelerating electrodes positioned on opposite sides of said output electrode system, and means for causing the electrons to follow orbital paths through said output electrode system and including means for producing an electromagnetic field within said output electrode system and parallel to the longitudinal axis of said envelope, and a rod electrode positioned axially within said electrode segments and adapted to be maintained at cathode potential during operation of said electron discharge device, and a first conductor connected to one of said electrode segments and a second conductor connected to another electrode segment and parallel to the first conductor, and means connecting said conductors together remote from said electrode segments providing an output transmission line circuit and a shield surrounding said output electrode system and said conductors.

14. An electron discharge device having a cathode for supplying a beam of electrons, an electrode for receiving the electrons in the beam, a first control electrode adjacent the cathode for modulating the electron stream, and a second electrode means surrounding the path of the electron stream adjacent the first control electrode and including electrodes surrounding said beam path and spaced by a gap lying in a plane transverse to the path of the beam, an output electrode means including a plurality of electrode segments surrounding the path of the beam and separated by gaps extending along the longitudinal axis of said beam, and means for causing electrons to follow orbital paths through said output electrode means and including means for producing a magnetic field along the axis of said beam.

15. An electron discharge device having an elongated envelope and containing a cathode for providing a stream of electrons and a collector for collecting said electrons, an electrode adjacent the cathode for modulating the stream of electrons from said cathode, a resonator surrounding said envelope and provided with a gap surrounding said envelope between said modulating electrode and said collector for providing a radio frequency field for velocity modulating the electrons from said cathode, a pair of screen and accelerating electrodes within said envelope and positioned on opposite sides of said gap, an output electrode system provided between said resonator and said collector and having electrode segments surrounding said envelope, said segments being spaced by a gap along said envelope, and means for causing electrons to follow orbital paths within said output electrode system and including means for producing an electromagnetic field within said output electrode system and parallel to the longitudinal axis of said envelope.

16. An electron discharge device having an elongated envelope and containing a cathode for

providing a stream of electrons and a collector for collecting said electrons, an electrode adjacent the cathode for modulating the stream of electrons from said cathode, a resonator surrounding said envelope and provided with a gap surrounding said envelope between said modulating electrode and said collector for providing a radio frequency field for velocity modulating the electrons from said cathode, an output electrode system provided between said resonator and said collector and having electrode segments surrounding said envelope, said segments being spaced by a gap along said envelope, and means for causing electrons to follow orbital paths along said output electrode system and including means for producing an electromagnetic field within said output electrode system and parallel to the longitudinal axis of said envelope.

17. An electron discharge device having an elongated envelope and containing a cathode for providing a stream of electrons and a collector for collecting said electrons, a grid adjacent the cathode for modulating the stream of electrons from said cathode and having an extended collar positioned closely adjacent the inner wall of said envelope, a resonator surrounding said envelope and provided with a gap surrounding said envelope between said modulating grid and said collector for providing a radio frequency field for velocity modulating the electrons from said cathode, a pair of screen and accelerating electrodes within said envelope and positioned on opposite sides of said gap, said resonator having an extended wall closely adjacent the tube envelope and surrounding the grid collar and one of the screen and accelerating electrodes, an output electrode system provided between said resonator and said collector and having electrode segments surrounding said envelope, said segments being spaced by a gap along said envelope, and means for causing electrons to follow orbital paths within said output electrode system and including means for producing an electromagnetic field within said output electrode system and parallel to the longitudinal axis of said envelope.

18. An electron discharge device having an elongated envelope and containing a cathode for providing a stream of electrons and a collector for collecting said electrons, an electrode adjacent the cathode for modulating the stream of electrons from said cathode, a resonator surrounding said envelope and provided with a gap surrounding said envelope between said modulating electrode and said collector for providing a radio frequency field for velocity modulating the electrons from said cathode, a pair of screen and accelerating electrodes within said envelope and positioned on opposite sides of said gap, an output electrode system provided between said resonator and said collector and having electrode segments surrounding said envelope, said segments being spaced by a gap along said envelope, and means for causing electrons to follow orbital paths within said output electrode system and including means for producing an electromagnetic field within said output electrode system and parallel to the longitudinal axis of said envelope, and a rod electrode positioned axially of said electrode segments and adapted to be maintained at cathode potential during operation of said electron discharge device.
